UNITED STATES PATENT OFFICE.

ANDREW WILHELM KOSKI, OF SCOFIELD, UTAH.

SLEIGH.

SPECIFICATION forming part of Letters Patent No. 581,595, dated April 27, 1897.

Application filed January 7, 1897. Serial No. 618,330. (No model.)

To all whom it may concern:

Be it known that I, ANDREW WILHELM KOSKI, a citizen of the United States, residing at Scofield, in the county of Carbon and 5 State of Utah, have invented a new and useful Sleigh, of which the following is a specification.

The invention relates to improvements in sleighs.

10 The object of the present invention is to improve the construction of that class of sleighs which are adapted to be propelled by the occupant and to provide one which may be effectually guided by the feet of the operator.

15 The invention consists in the construction and novel combination and arrangement of parts hereinafter fully described, illustrated in the accompanying drawings, and pointed out in the claims hereto appended.

20 In the drawings, Figure 1 is a perspective view of a sleigh constructed in accordance with this invention. Fig. 2 is a longitudinal sectional view of the same. Figs. 3 and 4 are transverse sectional views. Fig. 5 is a detail 25 perspective view of the steering-lever.

Like numerals of reference designate corresponding parts in all the figures of the drawings.

1 designates a sleigh having its runners 2 30 composed of rigid rear sections 3 and pivoted front sections 4, and the rear sections 3 are connected with the body of the sleigh in the usual manner by knees or supports 5.

The rear terminals of the front sections 4 35 are connected to the rigid sections 3 by pivots 6, and the upper or front terminals of the sections 4 are similarly secured to the front of the sleigh by pivots 7. The pivotal connections of the front sections of the runners per-

40 mit the latter to be shifted laterally of the sleigh to change the direction thereof, and they are caused to move simultaneously in the same direction by a cross-bar 8, which connects the front sections 4 between their 45 ends.

The sleigh is guided by a substantially T-shaped steering-lever 9, consisting of a head fulcrumed on a pivot 10 and a stem extending through an opening of the front of the 50 sleigh-body and engaging an eye or opening of the transverse bar 8. The pivot 10 is

mounted on the interior of the sleigh-body, and the steering-lever is provided at the center of its head with an eye 12, receiving the said pivot. The operator by pressing forward on either side of the head of the steering-lever swings the forwardly-extending stem of the same laterally, and thereby moves the front sections of the runners in the same direction. By this construction the sleigh 60 may be guided in any direction.

The movable front sections of the runners are supported by an arched brace 13, consisting of a transverse top portion, which is arranged in suitable guides 14, and depending 65 sides which are secured at their lower ends to the upper faces of the front sections of the runners.

The sleigh is propelled by means of an oscillating hand-lever 15, which is fulcrumed 70 between its ends in the slot of the bottom of the body of the sleigh, and its lower end is connected by a pitman 16 with a crank-shaft 17. The crank-shaft, which is journaled in suitable bearings of inclined supports 18, 75 carries a spur gear-wheel 19, which meshes with a pinion 20 of a transverse shaft 21. The transverse shaft 21 is also journaled in suitable bearings of the supports 18, and it carries propellers 22. The propellers consist 80 of wheels provided with blades adapted to engage the snow or ice and force the sleigh forward, and the sleigh may be geared to any desired speed.

It will be seen that the sleigh may be readily guided by the feet of the operator, and his hands are left free to be employed for propelling the sleigh.

What I claim is—

1. The combination of a sleigh having runners provided with movable front sections, a cross-piece connecting the front sections of the runners, and a T-shaped steering-lever fulcrumed within the body of the sleigh and arranged to swing horizontally, said lever being extended through the front of the sleigh and loosely engaging the said cross-piece, substantially as described.

2. The combination of a sleigh provided with runners having movable front sections pivoted at their terminals to the front of the sleigh and to the rear portions or sections of

the runners, and means for operating the movable sections of the runners, substantially as described.

3. The combination of a sleigh having runners provided with movable front sections pivoted at their terminals, a cross-piece connecting the front sections of the runners, a vertical pivot mounted on the body of the sleigh, and a T-shaped steering-lever mounted on the pivot, arranged to swing horizontally and loosely connected with the cross-piece, whereby the runners are shifted laterally when the steering-lever is swung horizontally, substantially as described.
4. In a sleigh, the combination of a body, runners composed of rigid rear sections, and

movable front sections pivoted to the rear sections and to the body of the sleigh, a guide mounted on the bottom of the body, a substantially U-shaped brace connecting the movable sections of the runners, arranged in the said guide and supporting the front portion of the body, and steering mechanism connected with the movable sections of the runners, substantially as described. 20 25

In testimony that I claim the foregoing as my own I have hereto affixed my signature in the presence of two witnesses.

ANDREW WILHELM KOSKI.
